UNITED STATES PATENT OFFICE.

JOHN O. MADISON, OF BROOKLYN, NEW YORK.

BUILDING CONSTRUCTION.

1,317,519.

Specification of Letters Patent. Patented Sept. 30, 1919.

Application filed January 6, 1919. Serial No. 269,750.

To all whom it may concern:

Be it known that I, JOHN O. MADISON, a citizen of the United States, residing at Brooklyn, county of Kings, and State of New York, have invented certain new and useful Improvements in Building Constructions, of which the following is a specification.

My invention relates to what may be termed building material for walls, floors, 10 ceilings and the like, and has for its object the provision of an improved trussed construction which will be adapted to carry heavy loads and be durable, of economical structure, fireproof, etc. My present invention relates to modifications of the general invention disclosed in my Patent No. 1,277,622, dated September 3, 1918, for trussed-sheet building material.

The patent referred to describes a construction embodying a pair of sheets, preferably of steel, which constitute the outer chord members of the trussed construction and which are rigidly connected together at certain intervals by intermediate web members composed of integral projections or depressions formed on one or both sheets and separated from each other laterally and longitudinally, these projections or depressions being of a depth many times the thickness of 30 the sheet, so as to produce a trussing effect.

My present invention relates to a modification of the above, in which a layer of concrete or other hard setting plastic material is formed with integral projections extending from one surface thereof, which projections are separated from each other laterally and longitudinally and are similar in construction and effect to the deep integral depressions provided on one or both of the 40 metal sheets described in my patent referred to above. This molded member of plastic material may, if desired, be provided with a reinforcing member, such as a sheet of wire mesh, which may, if desired, extend down into the integral projections of the molded member. Securing devices are embedded in the molded member and extend out through the surface on which the integral projections are formed, these securing devices preferably taking the form of bolts extending downwardly through the projections of the concrete member. The body of the concrete member constitutes the upper chord of a truss, and the lower chord 55 comprises a metal sheet which is secured to the apices of the integral projections of the

concrete member by means of the securing devices referred to. This metal sheet may be plane, in which case the projections on the molded concrete member form the web members of the truss. Or the metal sheet may be provided with deep integral depressions as in the case of my previous patent referred to above, in which case the apices of the depressions on the plate may be rigidly secured against the apices of the projections on the molded member by means of the securing devices referred to, in which case the projections on the molded member and the depressions formed on the metal sheet will together constitute the web members of the truss.

In order that a clearer understanding of my invention may be had, attention is hereby called to the accompanying drawings forming part of this application and illustrating certain embodiments of my invention.

In the drawings, Figure 1 represents a partial cross section through a construction embodying my invention; Fig. 2 is a partial cross section through a modified construction; and Fig. 3 is a top plan view of the construction illustrated in Fig. 2 with certain parts broken away.

Referring first to Fig. 1, one of the chord members of the truss comprises the sheet 1, preferably of pressed steel or other suitable metal. In the construction shown in Fig. 2, this member takes the form of a sheet 1' having integral depressions 2 formed therein, these depressions being formed by a suitable method such as pressing, rolling or molding the sheet, these depressions being of a depth many times the thickness of the sheet 1' as may readily be accomplished by pressing, drawing or metal rolling operations. In the construction shown in Fig. 1, the sheet 1 is illustrated as plane, sheets 1 and 1' shown in Figs. 1 and 2 being preferably formed of pressed steel or other suitable metal.

The member 3 comprises a layer of hard setting plastic material, such as concrete, which is so molded or formed as to provide a considerable number of projections 4 extending from one face thereof, these projections being of a depth many times the thickness of the sheet 1 or 1' and spaced apart laterally and longitudinally, preferably in a staggered relation. These integral depressions may be of any desired shape, but are

preferably of a frusto-conical shape. The plastic material member 3 may, if desired, be reinforced preferably by a sheet of wire mesh 5 or the like, embedded in the plastic material and extending throughout the same. If desired, this reinforcing member 5 may be so positioned in the mold when member 3 is formed as to extend into the projections 4, as is indicated at 6 in Fig. 1. The plastic material 3 is also provided with securing devices, such as bolt 7, which are embedded therein and extend out through the projections 4. These securing devices 7 may be anchored to the reinforcing member 5 as by 15 having the heads 8 of the securing devices engage the member 5. When the securing devices 7 extend downwardly through projections 4, as illustrated, they serve as additional reinforcing means for the projections. 20 The structure may be completed by securing the metal sheet 1 directly to the securing devices 7, as, for example, by extending bolts 7 through openings in the sheet 1 and screwing up the nuts of the bolts, as is indicated in Fig. 1. Or when a sheet 1' is 25 used for the lower chord member having integral depressions, such as are indicated at 2 in Fig. 2, the bolts may extend through openings in the apices or end portions of 30 the depressions 2 and may be secured in place by screwing up the nuts.

What I claim is:

1. In a trussed structure adapted to withstand heavy loads or stresses, the combination of a rigid metal-sheet constituting one chord member of the truss, a layer of plastic material formed with integral projections of a depth many times the thickness of said sheet, extending from one surface of said 35 layer and spaced apart laterally and longitudinally, and securing devices embedded in said material and extending through the apices of said projections, said sheet being secured directly by said securing devices to the apices of said projections, the body of 40 said plastic material constituting the opposite chord member of the truss and the integral projections constituting web members of the truss.
- 50 2. In a trussed structure adapted to withstand heavy loads or stresses, the combination of a rigid metal sheet constituting one chord member of the truss, a layer of plastic material formed with integral projections of a depth many times the thickness of said 45 sheet, extending from one surface of said layer and spaced apart laterally and longitudinally, and securing devices embedded in said material and extending therefrom, and secured rigidly to said sheet to hold the same

directly in engagement with the apices of said projections, the body of said plastic material constituting the opposite chord member of the truss and the integral projections constituting web members of the 55 truss.

3. In a trussed structure adapted to withstand heavy loads or stresses, the combination of a rigid metal sheet, constituting one chord member of the truss, a layer of plastic material formed with integral projections of a depth many times the thickness of said sheet, extending from one surface of said layer and spaced apart laterally and longitudinally, reinforcing material embedded in 70 and extending through said layer, and bolts embedded in said material and extending through the apices of said projections and through said sheet, and secured to said sheet to hold the latter directly against said apices 75 the body of said plastic material constituting the opposite chord member of the truss and the integral projections constituting web members of the truss.

4. In a trussed structure adapted to withstand heavy loads or stresses, the combination of a metal sheet having permanent integral depressions spaced apart laterally and longitudinally, a layer of plastic material formed with integral projections spaced in 80 the same manner as said depressions, and securing devices embedded in said layer and extending through said projections and the apices of said depressions to hold said sheet and layer rigidly, in spaced apart relation. 85

5. In a trussed structure adapted to withstand heavy loads or stresses, the combination of a rigid metal sheet constituting one chord member of the truss, a layer of plastic material formed with integral projections 100 of a depth many times the thickness of said sheet, extending from one surface of said layer and spaced apart laterally and longitudinally, a reinforcing metal member embedded in and extending through said layer 105 and into said projections, and securing devices embedded in said material and extending therefrom, and rigidly secured to said sheet to hold the same directly in engagement with the apices of said projections, the body of said plastic material constituting the opposite chord member of the truss and the integral projections constituting web members of the truss. 110

This specification signed and witnessed 115 this 3d day of January, 1919.

JOHN O. MADISON.
